US00D841650S

(12) **United States Design Patent** (10) Patent No.: **US D841,650 S**
Masin et al. (45) Date of Patent: **** Feb. 26, 2019**

(54) **RFID READER FOR RFID TAGS**

(71) Applicant: **Trovant, Ltd.**, Isle of Man (GB)

(72) Inventors: **Barbara P. Masin**, Santa Barbara, CA
(US); **Nick A. J. Smith**, Channel Islands (GB)

(73) Assignee: **Trovant, Ltd.**, Isle of Man (GB)

(**) Term: **15 Years**

(21) Appl. No.: **29/595,985**

(22) Filed: **Mar. 3, 2017**

(51) LOC (11) Cl. **14-02**

(52) U.S. Cl.

USPC **D14/426**; D14/431

(58) **Field of Classification Search**

USPC ..... D14/420, 426-431, 453, 346, 341, 347, D14/412, 138, 411, 167, 413, 496, 356, D14/203.3, 203.5, 203.7, 217, 218; D13/107, 184; 358/473, 484; 235/462.43, 462.45, 462.47, 462.48, 235/462.44, 462.46, 487, 472.01, 472.02, 235/145 A, 145 R, 462.49, 472.03, 494, 235/495, 482, 454; D10/78, 57, 2, 46, D10/52, 53, 81; 324/426; D3/273; 710/73; D18/7; 361/679, 728, 679.56, 361/683; 382/313, 321, 314, 318; 455/575.1, 561, 572, 41.2; 345/156, 168, 345/169, 172, 173, 87, 179, 183, 165, 345/166; 705/17, 18, 22-25; D16/206, D16/218, 202, 219, 208, 209; 356/328; 396/419, 423, 424; 374/130, 100, 121, 374/102, 141, 124, 170, 104, 103; 702/130, 135; 348/164, 165, 149, 333.01, 348/333.11, E5.043, E5.047, E5.09, 33, 348/82, E5.028, 347, 373, 374, 375, 66; 250/330, 351, 353, 332, 334, 358.1, 250/316.1, 338.1, 568, 555, 566, 569;

600/549, 474, 413, 473, 200, 184, 437, 600/427, 439, 109, 178, 180, 237, 241; D24/186, 185, 187, 152, 158, 133, 144, D24/146, 107, 112, 206, 200, 209, 215, D24/167, 214, 210; D21/333; D28/44, D28/48; D8/99; 359/214; 16/110.1, 16/430, 431; 439/133, 135; 433/29, 37, 433/72, 114, 116; 709/219, 201; 320/114, 115, 123; D26/37; 401/195; 362/118; D19/60, 62, 65-67, 71, 100, (Continued)

(57) **CLAIM**

The ornamental design for an RFID reader for RFID tags, as shown and described.

DESCRIPTION

FIG. 1 is a top, rear, and right side perspective view of an RFID reader for RFID tags, showing our new design.

FIG. 2 is a bottom, rear, and left side perspective view thereof.

FIG. 3 is a top, front, and left side perspective view thereof.

FIG. 4 is a bottom, rear, and right side perspective view thereof.

FIG. 5 is a top plan view thereof; and,

FIG. 6 is a bottom plan view thereof.
